UNITED STATES PATENT OFFICE.

ALFRED F. MEYER, OF MORTON, ILLINOIS, ASSIGNOR TO MORTON CORPORATION, OF MORTON, ILLINOIS, A CORPORATION OF ILLINOIS.

ELEVATOR STRUCTURE.

1,395,985.

Specification of Letters Patent.

Patented Nov. 1, 1921.

Application filed December 19, 1919. Serial No. 346,058.

To all whom it may concern:

Be it known that I, ALFRED F. MEYER, a citizen of the United States, residing at Morton, in the county of Tazewell and State 5 of Illinois, have invented certain new and useful Improvements in Elevator Structures; and I do hereby declare that the following is a full, clear, and exact description of the invention, which will enable others 10 skilled in the art to which it appertains to make and use the same.

This invention has reference to elevators, particularly of the type employed in handling grain in cribs and granaries.

15 The invention has to do with a stationary type of so-called vertical elevator wherein two legs are used for the up and down stretches or runs of the elevating chains, the same being spaced each side of a driveway, 20 and including a horizontal portion used as a "dump" portion acting as a conveyer for receiving grain from a wagon.

25 My main object is the provision of an elevator and a cross conveyer of dump portion so constructed throughout as to require no sprocket wheels, or wheels of any kind in fact, except those for driving purposes placed remotely from and outside the conveyer, to the end that friction may be reduced to a low point, and that there will be 30 no wheels or parts to cause trouble or lie in the way of the grain, especially ear corn, being handled.

35 A further object is to provide an elevator of the spaced-leg type, including a conveyer portion, the whole constituting a unitary structure having a guideway extending therethrough for a roller chain provided with buckets or flights.

40 Another important object is the construction of an elevator of the spaced leg type in which the conveyer-portion therefor is devoid of wheels of any kind and constructed whereby it can be placed in a very shallow 45 depression in the floor as distinguished by the usual types which require a considerable depth in the ground because of the use of wheels in their make-up.

50 Another object is the provision of adjustable hopper boards for a conveyer by which the material to be handled, while dumped in a body or in one bulk upon the

conveyer, can be controlled and permitted to feed to the drag chain as fast or as slowly as desired. 55

Still another object of my invention is that of providing an elevator-leg of pivotally connected parts so constructed that such parts may be adjusted to any angle found necessary to lie in and fit the roof 60 angle of a crib or other building.

With these and other objects in view the invention pertains also to certain details of construction to be pointed out herein and in the claims, it being understood that the invention is susceptible of minor changes without departing from the spirit and intent of such invention, and as falling within the scope of the said claims. 65

In the appended drawings forming part 70 of this application—

Figure 1 is an elevation of a building showing my improved elevator therein.

Fig. 2 is a plan of a portion of a building showing the elevator in horizontal section. 75

Fig. 3 is a vertical section of part of the conveyer portion of my elevator greatly enlarged from that shown in Fig. 1.

Fig. 4 is a transverse section of the conveyer portion shown in Fig. 3. 80

Fig. 5 is a side elevation of the upper portion of my improved elevator produced on a much larger scale than in Fig. 1.

Fig. 6 is a transverse section of the structure shown in Fig. 5. 85

Fig. 7 is a longitudinal section of part of what is shown in Fig. 5, on a much larger scale, and

Fig. 8 shows in perspective part of what 90 appears in Figs. 5 and 7.

Elevators of the spaced leg type, or those leaving a drive-way space between them, and including a conveyer-portion or dump, are commonly furnished with sets of wheels for carrying the drive chain and for driving purposes. But by reason of the required diameter of such wheels and the necessary space to accommodate them the said conveyer-portion is required to be deeply set 95 into the ground below the driveway floor. This depth is often as much as 36 inches or more and any trouble developing therein is difficult to reach because of the depth, and 100

the inaccessibility of the narrow framing comprised in the structure. Not alone is this a disadvantage, but the matter of expense of installation must also be taken into account. Again, the greater depth requires longer chains which means increased friction, additional difficulties with regard to chance breakage, and greater expense for the materials required.

10 It is my purpose to provide a structure, therefore, wherein the lowest portion of the conveyer-portion will not lie more than twelve or thirteen inches below the floor level and thus, with a given height of building, the elevating chain may be greatly reduced in length, while the parts of the structure may be readily reached from the drive-way. In addition, friction may be reduced to a minimum by providing a guide-way through which a chain provided with friction rollers can readily move.

15 A indicates a building in which the elevator, whose legs are designated by B, B', is installed. These legs are widely spaced, leaving a dryeway C between them, receiving bins for the materials to be elevated being denoted by E, F, G.

20 H indicates the conveyer-portion as a whole connecting the legs B, B' and lying just below the drive-way floor.

25 The said legs, the conveyer-portion H, and what may be termed the elevator head, J, compose a complete structure through which runs a single chain K, Fig. 3, made up of links L carrying rollers M at their places of pivotal connection, buckets N being supported between opposite chains, as most clearly shown in Fig. 4.

30 In order to accommodate the chains, the described parts of the elevator are provided with guide-ways throughout, there being such a guide-way O in each as shown in Figs. 2 and 4.

35 The conveyer-portion H may be a casting or it may be made of sheet metal or wood if desired, but in any event the guide-ways are such as to receive the chain and rollers into them but closed, as in the figure last named, in order to prevent loss of grain through 40 said guide-ways and also to prevent materials working through them from the outside into the drag space for the buckets.

45 Upon the upturned ends of the conveyer-portion are mounted the described vertical legs B, B' whose guide-ways are in register with those of said portion.

50 Between the legs the upper side of the said conveyer-portion is open, while downwardly and inwardly slanting boards P are placed therein as shown, constituting a shallow hopper to receive the material to be elevated. Mounted upon each of the boards P is a board Q adjustable laterally and secured by suitable means such as bolts R, 55 for example, by which the amount of mate-

rial let into the conveyer may be governed at will.

I have found it convenient and expedient to construct an elevator of this type so that its top or head may be adjusted in order to 70 snugly fit into any roof angle, thereby saving space and at the same time placing the discharge opening for the delivery spout as high as possible without the requirement of a cupola for that purpose. Since roof angles vary somewhat, I am enabled by my structure to adjust the elevator parts of any elevator taken from stock to the particular job to be fitted.

75 That is to say, B², B³ and B⁴ represent the upper portions or head portion of the elevator, of which B³ is a conveyer portion, the said portions being pivotally related. The structure for this purpose is best shown in Figs. 7 and 8, and while such structure is 80 shown as a connection between B and B² it applies to all of the parts mentioned. S and T are two arms pivotally connected at one of their ends at U, being secured to the portions B and B² in any suitable manner. 85 VV are two arc-shaped metal trough portions secured to B² and spaced from one another and flanged at 1, Fig. 8, to provide the proper guide for the chain K and its rollers M.

90 95 WW indicate companion trough portions secured upon the leg B to enter the portions V, Fig. 7, and having the flanges 2 for the purpose mentioned. The curves of these portions V and W are described from the pivot point V so that as the portion B² is moved upon its pivot to suit the roof angle the said portions VW will accommodate themselves, maintaining the guide-ways at all times for free working of the chains.

100 105 The portion B⁴ has the same relation to the leg B', and B³ is necessarily likewise adjustable upon B² and B⁴.

B³ is of two telescoping portions so that one may slip over the other to either increase 110 or decrease the distance between B² and B⁴ according to the angles taken by the latter.

Naturally the adjustment to accommodate the roof angles will shorten or lengthen the distance for the chain travel, which calls for 115 the change in chain length. When adjustments are made the whole structure may be secured in any desired manner, such as by supporting the parts from the roof for example.

120 The under side of the middle portion B³ is open so that the material elevated can be discharged from the buckets into the spout suspended therebeneath.

125 Any desired method of driving the chains K may be employed. As one of the ways, I show in Fig. 5 a pair of sprocket wheels 5, 6, carried on shafts 7. Each of the latter lies at the angle created between the portions B², B⁴ and the middle portion B³. The sides 130

of these portions are recessed at 8 to let the wheels into them for engaging the chains, see Fig. 7, said wheels being closed disks to prevent the grain falling from the 5 inclosure, the slight opening for clearance of the sprocket teeth being of no particular moment.

On one of the shafts is a sprocket wheel 9 over which is trained a drive chain 10 extending down to any source of power, not 10 shown. If desired, said shafts 7 may each carry a sprocket 11 to receive a chain 12 whereby the power transmitted by the chain 10 may be imparted to the sprockets 6 as 15 well.

The adjustability of the parts is obviously 20 of great convenience in an elevator of this type, being likewise adaptable to other forms or those having but a single leg through which both the ascending and descending stretches of chain move.

The pivotally connected arms S and T permit the parts to be adjusted readily to any angle within the limits of the portions 25 V, W, any given outfit being readily set up for use without extended fitting of parts or the expense attending the furnishing of the same.

In constructing the elevator throughout, 30 so as to use the roller chain traveling in guide-ways, the whole structure is simplified and is of less cost than one requiring sprocket wheel or wheels for carrying the elevating element, the chain K, but above 35 all there are thus no parts to present a constant source of annoyance, and the conveyer-portion can be placed in a very shallow space, as pointed out, where it can be reached easily and quickly.

40 I claim:

1. An elevator structure of the class described, including in its construction a single conveyer-portion comprising a trough open at its top, and a leg erected at each end of 45 and connected into the said portion, said legs being spaced to leave a driveway space between them, the said conveyer-portion and the legs including a continuous guide-way at each side, an elevating element within the 50 guideways, and rollers arranged to travel in the guideways, supporting the element, the conveyer-portion being unobstructed by other internal mechanism.

2. An elevator structure of the class described including in its construction a single conveyer-portion comprising a trough open at its top, and a leg erected at each end of 55 and connected with the same, leaving a driveway space between said legs above said 60 conveyer-portion, there being a guide-way in and extending along each side of the conveyer-portion and continuing in each side of each leg, and an elevating element supported wholly within, arranged to travel 65 along the guide-way, and rollers supporting

the element, themselves supported within the guideways.

3. In combination, an elevating structure including a pair of upstanding legs spaced to leave a driveway space between them, and 70 having a conveyer-portion open at its top disposed beneath said driveway space connected with and rounded into such legs, a guideway in opposite walls of the legs and the conveyer-portion, and a conveying element in the structure including a series of rollers, adapted to travel within said guideways, said conveyer-portion being unobstructed by other internal mechanism. 75

4. In combination an elevating structure 80 including a pair of upstanding legs arranged to leave a driveway space between them and having a conveyer-portion open at its top beneath said driveway space, said conveyer-portion and said legs having a continuous 85 groove in opposite walls thereof, and a chain including elevating devices arranged to travel throughout the described parts including rollers adapted to travel within said grooves, said conveyer-portion being devoid 90 of other internal mechanism.

5. In combination, a pair of elevator legs spaced from one another to leave a driveway space between them, a conveyer-portion open at its top beneath said driveway space but 95 otherwise closed, the same being curved into and connected with the said legs, and devoid of internal mechanism, said legs and conveyer portion having a continuous groove 100 in opposite walls thereof, a conveyer element arranged to travel throughout the described parts including elevating devices substantially filling the cross-sectional space within the conveyer, rollers carrying said chain arranged to travel within the guideways, and 105 a power drive engaging the chain.

6. An elevator structure including a pair of legs spaced to leave a driveway space between them, an open-top conveyer-portion beneath the driveway space connected into 110 the legs, said legs and said portion having a continuous guideway in opposite walls, an elevating chain adapted to travel within the guideways including elevating devices thereon, a member overhanging the receiving 115 space of the conveyer-portion lying in close proximity to the path of travel of the elevating devices and adjustable to constrict the opening of said conveyer.

7. An elevator structure including a pair 120 of legs spaced to leave a driveway space between them, an open-top conveyer-portion beneath the driveway space connected into the legs, said legs and said portion having a continuous guideway in opposite walls, an elevating chain adapted to travel within the guideways including elevating devices thereon, a pair of members overhanging the receiving 125 space of the conveyer lying in close proximity to the path of travel of the 130

elevating devices, one of them being adjustable to constrict the opening of said conveyer.

8. An elevator structure including a pair of legs spaced to leave a driveway space between them, an open-top conveyer-portion beneath the driveway space connected into the legs, said legs and said portion having a continuous guideway in opposite walls, 10 an elevating chain adapted to travel within the guideway including elevating devices thereon, a pair of members overhanging the receiving space of the conveyer lying in close proximity to the path of travel of the 15 elevating devices, the same being adjustable in the direction of one another for constricting the opening of said conveyer.

9. In combination, a building including a drive-way and a bin at each side of the same, 20 an elevator including a leg erected each side of said drive-way, and a head, a conveyer-portion lying beneath the floor of the driveway, open at its top, connecting the legs, there being a continuous guide-way extending 25 throughout the structure at opposite sides thereof, the said structure being devoid of internal mechanism, and an endless elevating element including friction rollers disposed in the guide-ways, and an external 30 power drive engaging the said element.

10. An elevator including in its construction a hollow leg portion, a support, a hollow portion pivotally mounted on the support adapted to have a position at an angle 35 to the leg portion, the pivot of the second named portion lying at the point of crossing of two lines each extending from and lying perpendicularly to the axis of the bore of one of the portions, each said portion 40 having a tubular arc shaped extension adapted to telescope one another.

11. An elevator including in its construction a hollow leg portion, a support, a hollow portion pivotally mounted on the support 45 adapted to have a position at an angle to the leg portion, both portions having a guideway in each of two walls thereof, the pivot of the second named portion lying at the point of crossing of two lines each extending from and lying perpendicularly to the axis of the bore of one of the portions, each said portion 50 having a tubular arc shaped extension adapted to telescope one another, each extension having a guideway 55 in opposite walls corresponding in position to those of the described portions.

12. An elevator including in its construction a pair of spaced legs, a portion pivoted to the upper end of each, and a conveyer 60 portion connected to and lying between the said portions.

13. An elevator including in its construction a pair of spaced legs, a portion pivoted to the upper end of each, and a conveyer 65 portion disposed between and connected to

both the said pivoted portions, and a conveyer-chain extending through the legs, each of the said portions, and said conveyer portion.

14. An elevator including in its construction 70 a pair of spaced legs, a portion pivoted to the upper end of each, and a conveyer-portion disposed between and connected to both the said pivoted portions, and a conveyer-chain extending through the legs, each 75 of the said pivoted portions and said conveyer-portion, the latter being open at its lower side.

15. An elevator including in its construction 80 a pair of spaced legs, a portion pivoted to the upper end of each, and telescoping sections disposed between and pivoted each to one of the portions.

16. An elevator including in its construction 85 a pair of spaced legs, a portion pivoted to the upper end of each, telescoping sections disposed between and pivoted each to one of the portions, there being a guideway extending through the several portions at each side thereof, and an elevating device 90 adapted to move through the guideway.

17. An elevator structure including a pair 95 of spaced legs, each having a part surmounting it, each of the latter extending in the direction of the other substantially the form of an A, the legs and the described parts, each including a guideway at opposite sides, and a chain adapted to travel in the guideways.

18. An elevator structure including a pair 100 of spaced legs each having a part surmounting it, each of the latter extending in the direction of the other substantially the form of an A, the legs and the described parts, each including a guideway at opposite sides, 105 a chain adapted to travel in the guideways, and means to drive the chain.

19. An elevator structure including a pair 110 of spaced legs, an arched head-portion having its extremities connected with each leg forming a conveying portion from one leg toward the other, and a chain adapted to travel through the described structure.

20. An elevator structure including a pair 115 of spaced legs, an arched head-portion comprising pivotally related telescoping parts having substantially the form of an A, its ends connecting with said legs, said head portion adapted to be changed in form to 120 adapt it to various roof angles of a building in which it may be installed.

21. An elevator including in its construction 125 a pair of spaced legs, a pair of angled portions inclined toward one another, each surmounting one of the legs, a substantially horizontal conveyer portion connecting the portions, a drag-chain adapted to travel through the legs, and the several portions, and a drive wheel engaging the chain at each 130

end of the said conveyer portion at the junction thereof with said angled portions.

22. An elevator structure comprising a pair of legs spaced to leave a driveway space between them, a conveyer portion beneath the driveway space connecting the legs, an arched head-portion having its extremities connected with each leg forming with the leg and the conveyer-portion a continuous

runway, a chain adapted to travel through the described structure, and means for driving the chain.

In testimony whereof I affix my signature in presence of two witnesses.

ALFRED F. MEYER.
